DESIGN FOR A SERVICE STATION BUILDING OR THE LIKE

Ralph O. Munson, Chicago, Ill., assignor to Standard Oil Company, Chicago, Ill., a corporation of Indiana

Application May 31, 1939, Serial No. 85,255

Term of patent 14 years

To all whom it may concern:

Be it known that I, Ralph O. Munson, a citizen of the United States, residing at Chicago, in the county of Cook and State of Illinois, have invented a new, original, and ornamental Design for a Service Station Building or the like, of which the following is a specification, reference being had to the accompanying drawing, forming part thereof, in which:

Figure 1 is a front perspective view of a service station building or the like showing my design; and

Figure 2 is a horizontal section of the building shown in Figure 1.

I claim:

The ornamental design for a service station building or the like, substantially as shown.

RALPH O. MUNSON.
